DESIGN FOR A WATER HEATER CABINET

George W. Walker, Pleasant Ridge, Mich., assignor to The Timken-Detroit Axle Company, Detroit, Mich., a corporation of Ohio

Application April 27, 1945, Serial No. 119,279

Term of patent 14 years

(Cl. D81—2)

To all whom it may concern:

Be it known that I, George W. Walker, a citizen of the United States, residing at Pleasant Ridge, in the county of Oakland and State of Michigan, have invented a new, original, and ornamental Design for Water Heater Cabinet, of which the following is a specification, reference being had to the accompanying drawing, forming a part thereof.

Figure 1 is a front perspective view of a water heater cabinet embodying my new design.

Figure 2 is a side elevation of the cabinet of Figure 1.

Figure 3 is a top plan view of the cabinet of Figure 1.

I claim:

The ornamental design for a water heater cabinet, substantially as shown.

GEORGE W. WALKER.
